ANTENNA WHIP

John Schuller, South Euclid, Ohio, assignor to Orion
Industries, Inc., Los Angeles, Calif.

Filed Mar. 27, 1972, Ser. No. 238,723

Term of patent 14 years

Int. Cl. D14—03

U.S. Cl. D26—14 F

FIG. 1 is a front elevation of an antenna whip showing my new design;

FIG. 2 is an enlarged fragmentary front elevation thereof; and

FIG. 3 is a top plan view thereof.

I claim:

The ornamental design for an antenna whip, as shown.
